DESIGN FOR A PRESSURE COOKER

Ernoll Wayne La Barre, New York, N. Y., assignor
of one-half to Herbert C. Leech, doing business
as Herbert C. Leech Illustrators, New York,
N. Y.

Application January 9, 1947, Serial No. 136,019

Term of patent 7 years

(Cl. D44—1)

To all whom it may concern:

Be it known that I, Ernoll Wayne La Barre, a citizen of the United States of America and a resident of New York, in the county of New York and State of New York, have invented a new, original, and ornamental Design for Pressure Cooker, of which the following is a specification, reference being had to the accompanying drawing forming part thereof, in which—

Fig. 1 is a side elevation of a pressure cooker, embodying my design.

Fig. 2 is a top plan view thereof.

Fig. 3 is a view similar to Fig. 2 with the handle in the open position.

I claim:

The ornamental design for a pressure cooker, as shown.

E. WAYNE LA BARRE.
